CLAIM

The ornamental design for a combined illuminated clipboard and writing instrument for attachment to an automobile steering wheel, as shown and described.

DESCRIPTION

FIG. 1 is a top, left front perspective view of a combined illuminated clipboard and writing instrument for attachment to an automobile steering wheel showing my new design;

FIG. 2 is a bottom, right front perspective view thereof;
FIG. 3 is a bottom, right front perspective view thereof
with the clamp member in an extended position; and,
FIG. 4 is a right side elevational view thereof with the
writing instrument in an alternate position.

The rear of the article is substantially plain and unornamented.

FIG. 3

FIG. 4
